[57] CLAIM

The ornamental design for a fire hose carrying tool, as shown and described.

DESCRIPTION

FIG. 1 is a front left perspective view of a fire hose carrying tool showing our new design;

FIG. 2 is an elevational view of one side, the opposite side being a mirror image thereof, the broken lines forming no part of the design but indicating the manner in which the top layers of a roll of medium size fire hose are lodged within the tool while providing a hand grip to lift and carry the fire hose roll;

FIG. 3 is an elevational view of the left-hand end thereof;

FIG. 4 is an elevational view of the right-hand end thereof;

FIG. 5 is a top plan view; and,

FIG. 6 is a bottom plan view.
